P. MUELLER.
DRYING APPARATUS.
APPLICATION FILED JULY 30, 1915.

1,255,915.

Patented Feb. 12, 1918.

Inventor:
Paul Müller,
by Asst. Commissioner
Aug.

UNITED STATES PATENT OFFICE.

PAUL MUELLER, OF BERLIN, GERMANY.

DRYING APPARATUS.

1,255,915.

Specification of Letters Patent. Patented Feb. 12, 1918.

Application filed July 30, 1915. Serial No. 42,698.

To all whom it may concern:

Be it known that I, PAUL MUELLER, a subject of the King of Prussia, and residing at Berlin, S. W., in the Kingdom of Prussia and German Empire, have invented certain new and useful Improvements in Drying Apparatus, of which the following is a specification.

My invention relates to apparatus for 10 drying wet sheets of paper or cloth, such as prints of drawings, photoprints and the like, and particularly to an apparatus designed to dry the wet sheets in a very short time.

15 The object of my invention further is to provide an apparatus adapted for use with a heating device or any heating agent and which will dry sheets uniformly and without damaging them.

20 My invention is shown in the accompanying drawings, wherein a perspective view of my new apparatus in its preferred construction is shown.

My apparatus is intended for use with 25 prints and the like of all sizes. As shown, the front board *a* and the rear board *m*, made of galvanized or enameled sheet iron, or other suitable material that will not discolor wet paper sheets, are inclined toward 30 each other so that the side walls *c* form each an isosceles triangle, while the upper edge *k* is preferably rounder, so that large sheets may be placed smoothly over the said edge to hang both over the front board *a* and over 35 the rear board *m*. Air holes *r* may be provided in the top of the side walls *c*.

At the bottom a gas pipe *s* is mounted 40 having its one end closed while the other end is provided with a valve *t* and a nipple *u* for the connection with a gas conduit, not shown, by means of a flexible tube, or the like. The pipe *s* carries a burner *h*. Preferably a heat distributing plate *i* is arranged between the front and rear board a little 45 above the said burner. The longitudinal corners *v* of the plate *i* are slightly bent upward to cause the hot air arising from the burner to come in contact with the inner faces of the front board *a* and rear board *m*.

50 At the bottom edge of the front board *a* and, if desired, also of the rear board *m* a narrow trough *w*, may be provided to receive the water flowing down from the wet sheets *e* placed on the board.

55 What I claim is:

1. A drying apparatus for wet sheets of

paper, or other material comprising one continuous flat surface formed of two oppositely inclined faces, and a heat radiating means directly underneath said faces. 60

2. A drying apparatus for wet sheets of paper or other material comprising a continuous flat surface of triangular cross-section provided with a rounded upper edge and a heat radiating means underneath said 65 surface.

3. A drying apparatus for wet sheets of paper or other material, comprising a continuous flat surface of triangular cross-section, side-walls inclosing the open space underneath said surface, and a heat radiating means arranged in the said open space. 70

4. A drying apparatus for wet sheets of paper or other material comprising a continuous flat surface of triangular cross-section, provided with a rounded upper edge, side-walls inclosing the open space underneath said surface, and a heat radiating means arranged in said open space, said side-walls being provided with air-holes near 80 their upper ends.

5. A drying apparatus for wet sheets of paper or other material, comprising a continuous flat surface, forming two oppositely inclined faces, side-walls inclosing the space 85 between said faces, a gas-pipe secured to said side-walls, and a burner carried by said gas-pipe intermediate between said faces.

6. A drying apparatus for wet sheets of paper or other material comprising a continuous flat surface, forming oppositely inclined faces, side-walls inclosing the space between said faces a gas-pipe secured to said side-walls, and a burner carried by said gas-pipe intermediate between said faces, said 95 side-walls being provided with air-holes near their upper ends.

7. A drying apparatus for wet sheets of paper or other material comprising a continuous flat surface, forming oppositely inclined faces, side-walls inclosing the space between said faces a gas-pipe secured to said side-walls, a burner carried by said gas-pipe intermediate between said faces, and a heat distributing plate, located above said burner 100 and extending between said faces and said side-walls. 105

8. A drying apparatus for wet sheets of paper or other material comprising a continuous flat surface, forming oppositely inclined faces, side-walls inclosing the space between said faces a gas-pipe secured to said 110

side-walls, a burner carried by said gas-pipe intermediate between said faces, and a heat distributing plate, located above said burner and extending between said faces and said side-walls, said side-walls being provided with air holes near their upper ends.

In testimony whereof I have affixed my signature in presence of two witnesses.

PAUL MUELLER.
